LEIGH JAMES STEPHENSON, OF OAKMONT, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed December 8, 1925. Serial No. 74,220.

My invention relates generally to controllers for motor vehicles, and more particularly to switching devices associated with controllers for controlling the line-switching circuit.

The object of the invention, generally stated, is the provision of a switching mechanism for controllers that shall be simple and efficient in operation, and readily and economically manufactured.

A more specific object of the invention is to provide means for the control of a line-switch-actuating circuit when the controller is in an operative position and the breaking of the actuating circuit independently of the switch actuating means when the controller is in its off position.

A further object of the invention is to insure safety in operation when more than one controller is connected in a circuit.

It is also an object of the invention to so construct and assemble the apparatus as to facilitate the work of replacement and repair of parts subjected to the greatest wear.

Other objects of the invention will, in part, be obvious and, in part, will appear hereinafter.

The invention, accordingly, is disclosed in the embodiment thereof shown in the accompanying drawing, and comprises the features of construction, combinations of elements and arrangement of parts which will be exemplified in the construction hereinafter set forth and the scope of the application of which will be indicated in the claims.

For a fuller understanding of the nature and objects of the invention, reference should be had to the following detailed description, taken in connection with the accompanying drawing, in which:

Figure 1 is a horizontal sectional view of one embodiment of the device constructed in accordance with this invention;

Fig. 2 is a view in side elevation, partly in section, showing features of the construction;

Fig. 3 is a view in side elevation, with a portion of the structure removed to show the relative positions of the operating members; and

Fig. 4 is a diagram of circuit connections that may be used when two controllers are mounted on a motor vehicle.

Referring now to the drawing, 10 design-

nates a controller drum, of any well-known type which is fixed to a shaft 11 that is rotatably mounted in a suitable casing 12. As will be observed, the shaft 11 projects above the casing 12 to receive the drum-actuating mechanism. In this particular construction, 60 the drum-actuating mechanism comprises an auxiliary shaft 13 that is rotatably mounted in alignment with the drum shaft 11. The operation of the auxiliary shaft may be effected by means of a handle 14 65 of any well-known type.

A lost-motion connection is provided between the auxiliary shaft 13 and the main shaft 11, comprising two dogs, one attached to each shaft. As will be observed by reference to Fig. 1, each dog is provided with two spaced projections or curved lugs designated 15 and 16 and 17 and 18, respectively, which intermesh.

In order to obtain a movement of the 75 shaft 13 relative to the shaft 11 to effect the operation of a switching device to be herein-after described, the intermeshing projections on the dogs are proportioned to permit their relative movement through a predetermined 80 angle. In this particular construction, a movement of approximately 30° will suffice.

As shown in Figs. 2 and 3, an auxiliary drum 19 is mounted on the drum shaft 11. This auxiliary drum may be fixed to the 85 shaft in any suitable manner so that it will rotate with the drum 10. Two contact segments 20 and 21 are mounted on the auxiliary drum 19 and extend substantially around its circumference. In order to prevent the closure of the line switch of the motor vehicle before the drum 10 reaches its first operative position, as will be described hereinafter, the contact segment 20 is disposed somewhat in the rear of the contact 90 segment 21.

With a view to establishment of electrical connection between the contact segments 20 and 21 during the operation of the controller, two contact members or fingers 22 100 and 23, which are electrically connected to the contact segments 20 and 21, respectively, are provided. These contact members 22 and 23 are similar in construction and mounted in substantially the same manner; 105 therefore it will suffice to describe one of them.

As illustrated in Fig. 3, the contact mem-

ber 22 is mounted at right angles to the contact segments 20 and 21 and has formed, on its lower end, a curved portion shaped to seat on a block 24. In order to retain contact member 22 in operative position, a spring 25 is mounted on a screw 26, which engages a threaded opening that is provided in the block 24. In this manner, the contact member 22 is resiliently mounted so as to permit movement of its upper end.

Since contact members, such as 22 and 23, in service are continually subjected to arcing, they soon become coated with carbon or burned, necessitating their replacement. In order to facilitate such replacement of these contact members 22 and 23, their lower ends are bifurcated, as shown at 28, so that they may be readily withdrawn or reset in position without removing any of the other members of the switching mechanism.

In order to electrically connect the contact members 22 and 23, a switching member, shown generally at 29, is provided and mounted on the upper dog which may be actuated by the controller handle 14. As shown, in Fig. 1 the switching member 29 comprises two contact screws 30 and 31, the heads of which are clamped between two semicircular insulating members 32 and 33 that are fixed to the upper dog in any suitable manner, such as by the use of screws 34. Extending between the heads of the contact screws is a conductor 35 which, in this particular construction, is flexible so that the switch member may be easily mounted and removed. As illustrated the angular spacing of the contact screws 30 and 31 is the same as the angular spacing of the contact members 22 and 23.

It is further pointed out that the contact screws 30 and 31 are disposed on the upper dog so that they engage the contact members 22 and 23 just before the co-operating projections of the upper and lower dog engage, as the handle 14 is rotated forwardly. In this manner, electrical connection may be established between the contact members 22 and 23 by rotating the handle 14 forward relative to the drum, and the electrical connection thus established may be broken by rotating the handle backwardly.

In this embodiment of the invention, in order to connect the contact segments 20 and 21 in the line-switch actuating circuit, contact fingers 36 and 37 are removably mounted on a casing 38, which is provided for enclosing the switching mechanism. These contact fingers are mounted on an insulating block 39, which may be removably attached to the casing by means of bolts 40. As shown in Fig. 2, the contact fingers 36 and 37 are disposed in alinement with the contact segments 20 and 21, respectively.

Referring now to the diagram of connections shown in Fig. 4, it will be seen that

the actuating coil 43 of a line switch 44 is connected to the contact fingers 37 and 39 of the two controllers, which are located at opposite ends of the vehicle. In order to complete the circuit through the line-switch-actuating coil 43, grounded contact segments 41 are provided on the controllers and disposed to engage contact fingers 42 when the controller drums are moved to their initial operative positions. As shown, an interlock 45 is provided on the switch 44 to establish a holding circuit when the line switch is actuated. As in the usual construction of controllers of this kind, the grounded contact segments 41 engage their contact fingers 42 only when the controller is in its initial operative position.

The upper contact finger 36 of my switching mechanism is connected through a manually operable switch 46 to current-collector 47 which may be fed from a trolley 48, in accordance with the usual practice. A resistor 49 is connected in the line-switch-actuating circuit to restrict the flow of current to the ground connections 41.

In the operation of either controller, when it is desired to close the motor circuits, the corresponding handle 14 is rotated in a forward direction, first taking up the lost motion between the shaft 13 and the shaft 11 and projecting the contact screws 30 and 31 into engagement with the contact members 23 and 22, respectively. Since the contact segment 21 extends in advance of the contact segment 20, the contact finger 37 is in engagement therewith at this time, as shown in Fig. 2. Consequently, the contact segment 21 is connected through line-switch coil 43 to the contact finger 42 of the controller 10. In this first position of the handle 14, the contact segments 20 and 21 are electrically connected through the switch member 29, as previously described.

When the handle 14 is moved another step forward, the grounded contact member 41 is projected into engagement with the contact finger 42, and the contact segment 20 into engagement with the contact finger 36. In this manner, the line-switch-actuating circuit is closed, and current flows from trolley 48 through current-collector 47, switch 46, contact finger 36, contact segment 20, contact member 22, contact screw 31, conductor 35 and contact screw 30 of switch member 29, contact member 23, contact segment 21, contact finger 37, resistor 49, line-switch-actuating coil 43, and contact finger 42, to the grounded contact member 41 that is carried by the controller drum. The line switch 44 is immediately closed, and the interlock 45 is actuated to complete a holding circuit through the actuating coil 43 to ground at 49, thus maintaining the closure of line-switch 44 independently of controller 10.

Assuming that the handle 14 is rotated counter-clockwise to the extent of the lost motion that is provided between the intermeshing lugs, such as 15 and 17, thus moving the contact screws 30 and 31 out of engagement with the contact member 23 and 22, respectively, the line-switch-actuating circuit is immediately broken. However, the controller drum 10 has not thereby been rotated counter-clockwise, and the line-switch-actuating circuit may be reestablished by the rotation of the handle clockwise to again actuate the switch member 29. Thus, while the controller 10 remains in its first operative position, the motors may be actuated to move the car forward step by step through the operation of the line switch only. This process of moving the car is well known as "inching".

In order to emphasize the advantages of constructing the control mechanism for the line-switch-actuating circuit with the contact segment 20 set behind the contact segment 21, an example of what might happen if the contact segments were the same length will be explained. Assume that it is desired to operate the motor vehicle through the actuation of the controller shown at the left of Fig. 4, and, the vehicle being in traffic, that the operator desires to operate according to the process known as "inching".

Ordinarily, when the operator or motor-man is using one controller, the reversing key is removed from the other controller and the drum of the latter is locked. However, this does not prevent unauthorized persons from actuating the shaft 13 to take up the lost motion.

Let us assume that the controller shown at the right of Fig. 4 is provided with two contact segments similar to 21 and that its shaft 13 has been rotated forward by an unauthorized person to take up the lost motion, thereby actuating the switch member 29, and that the controller on the left has been set by the motor man in its first operative position, so that he may open and close the line switch 44 by oscillating the handle 14.

When the operator oscillates the handle 14 counterclockwise or backward, in order to insure safety in operation, the line switch 44 should immediately open. However, in this particular case, the switch 29 of the right-hand controller is closed and current flows from the trolley 48, through switch 46, contact segment 20 (if the same length as the contact segment 21), switch 29, contact segment 21, contact finger 37, resistor 49, line-switch-actuating coil 43, and contact finger 42 of the controller to the left, to the grounded contact member 41. Consequently, it will be impossible for the operator to open the line switch without moving the left-hand controller 10 from its initial posi-

tion and so he is unable to "inch" the car along.

The advantage of applicant's construction is therefore evident, since it will be readily understood that unauthorized persons, by actuating the shaft 13 of one controller to take up the lost motion, can, in no way, affect the control of the motor vehicle thereby.

Since certain changes may be made in the above construction and different embodiments of the invention may be made without departing from the scope thereof, it is intended that all matter contained in the above description or shown in the accompanying drawing shall be interpreted as illustrative, and not in a limiting sense.

I claim as my invention:

1. In a controller, the combination with a drum, an actuating handle for the drum and a lost-motion connection between the handle and drum, of means for controlling a switch-actuating circuit comprising contact members disposed to move with the drum and to be connected into the circuit and adapted to prevent the closure of the switch until the drum has been moved to its first operative position, and means operated by the handle for making and breaking circuit connections between said contact members.

2. In a controller, the combination with a drum, an actuating handle for the drum and a lost-motion connection between the handle and drum, of means for controlling a switch actuating circuit comprising contact members disposed in fixed relation to the drum to move with the latter, contact fingers for connecting the contact members in the switch actuating circuit, and means disposed to be operated by the handle when moved relative to the drum to cooperate with the contact members to control the switch actuating circuit, said contact members being positioned relative to the drum to permit the movement of the drum into its initial contacting position before the switch actuating circuit is closed.

3. In a controller, the combination with a drum, an actuating handle for the drum and a lost-motion connection between the handle and drum, of means for controlling a switch-actuating circuit comprising contact segments disposed to move with the drum, means operated by the handle for making and breaking electrical connection between the contact segment, and means for connecting the contact segments in the switch-actuating circuit, said segments being disposed to prevent the closure of the switch-actuating circuit before the drum reaches its first operative position.

4. In a controller provided with a drum, means for controlling a switch-actuating circuit comprising, in combination, contact

segments movable with the drum, resiliently mounted contact members electrically connected to the contact segments, and means movable independently of the drum to bridge the contact members.

5. In a controller provided with a drum, means for controlling a switch-actuating circuit comprising, in combination, contact segments movable with the drum, resiliently mounted contact members electrically connected to the contact segments, means movable independently of the drum to bridge the contact members, and means for connecting said contact segments in the switch-actuating circuit, said connecting means and contact segments being disposed relative to one another to prevent the closure of the switch before the drum reaches its first operative position.

10. 6. In a controller provided with a drum, means for controlling a switch-actuating circuit comprising, in combination, contact segments disposed for movement with the drum, resiliently mounted contact members electrically connected to the contact segments, means movable independently of the drum for making and breaking electrical connections between the contact segments, and means for connecting said contact segments in the switch-actuating circuit, one of said contact segments being disposed in the rear of the other and so located relative to the drum as to prevent the closure of the switch-actuating circuit before the drum reaches its first operative position.

15. 7. In a controller, the combination with a main drum, a handle for actuating the drum and a lost-motion connection between the handle and drum, of means for controlling a switch-actuating circuit comprising an auxiliary drum mounted to move with the main drum, two contact segments carried by said auxiliary drum, one of said contact segments being disposed in the rear of the other, contact members resiliently mounted and electrically connected to said contact segments, and switching means disposed for movement with the handle as it moves relative to the drum for making and breaking electrical connection between said contact members.

20. 8. In a controller, means for controlling

a circuit comprising an auxiliary drum disposed for rotation, contact segments mounted on the auxiliary drum, one of said segments being disposed in the rear of the other, contact members resiliently mounted and electrically connected to the contact segments, and means movable relative to the auxiliary drum for making and breaking electrical connection between the contact members.

25. 9. In a controller, in combination, a main contact-carrying drum, an auxiliary drum disposed to move with the main drum, an actuating handle for the main drum, a lost-motion connection between said handle and main drum, two contact segments carried by the auxiliary drum, one of said contact segments being disposed in the rear of the other, contact members resiliently mounted and electrically connected to the contact segments, and a bridging member disposed for operation by said handle as it moves relative to the drum to make and break electrical connection between the contact members.

30. 10. In a controller, in combination, a drum, a handle for actuating the drum, intermeshing members interposed between the handle and the drum, said intermeshing members being disposed to permit a predetermined movement relative to one another, resilient contact members carried by one of the intermeshing members, and a bridging member carried by the other intermeshing member and disposed to engage the resilient contact members, thereby to effect switching operations when the handle is oscillated.

35. 11. In a controller, in combination, a drum, a handle for actuating the drum, intermeshing dogs interposed between the handle and drum, said dogs being disposed to permit a predetermined relative movement, spring-pressed contact members carried by one of the dogs, a bridging member carried by the other dog, the bridging member being disposed to engage the spring-pressed contact members, thereby to effect switching operations as the handle is oscillated.

40. In testimony whereof, I have hereunto subscribed my name this first day of December 1925.

LEIGH JAMES STEPHENSON.
